SECURING DEVICE

Gilbert S. Watters, Davenport, Iowa

Application March 11, 1950, Serial No. 149,066

5 Claims. (Cl. 292—137)

1

Buildings of hospitals for the insane and the like must confine the inmates with certainty under normal conditions; and in emergencies, such as fire, they must release the inmates quickly and with equal certainty.

This invention relates to securing devices for openwork guards for exit openings in such buildings, and has for its principal object to insure that the guards will remain secure normally but can be quickly and certainly released in an emergency.

Generally speaking, this is accomplished by providing securing devices each having a base or body portion adapted to be made fast to the building permanently as by bolts or other suitable means and a locking portion normally securing the guard against opening but deformable by suitable force, such as a blow with a fireman's ax, to make it inoperative and release the guard.

In the accompanying diagrammatic drawings:

Fig. 1 is a perspective view of a window with an openwork guard equipped with securing devices embodying the invention;

Figs. 2 and 3 are sectional views indicated by the lines 2—2 and 3—3 of Fig. 1;

Fig. 4 is a perspective view illustrating a modification of the fastening means;

Fig. 5 is a front elevation of a window and guard equipped with another form of securing device embodying the invention;

Fig. 6 is an end view looking from the left in Fig. 5;

Fig. 7 is a section taken on the line 7—7 of Fig. 5;

Fig. 8 is a similar section of a slight modification; and

Fig. 9 is a front elevation corresponding to Fig. 5 but with the bars of the guard arranged in horizontal instead of vertical position.

In Fig. 1, 10 indicates a window frame equipped with a sash 11 and adapted to be permanently installed in a building.

12 indicates generally an openwork guard including a plurality of upright rods 13 welded at 14 to horizontal rails or bars 15.

The rod 13 at the right in Fig. 1 has its end portions received in suitable openings in hinged brackets 16 secured to the building whereby the guard is mounted to swing hinge-like, about the axis of the rod 13 to open the window.

At the left in Fig. 1, there is an upright rod 17, which serves as a latch bar and is associated with securing devices which make it fast for normal purposes, and thus secure the guard in closed position, but which may be quickly and surely released in an emergency.

2

The lower end of the rod 17 passes through an opening 18 in an arm 19 and comes to rest at the bottom on an arm 20, both of those arms being on a bracket generally indicated at 22 and here shown in a form including a rear portion 24 and a front portion 25 fastened together by rivets 26.

The upper end of the rod 17 passes through an opening 27 in an arm 28 on a fixed bracket 29, and has its extreme upper end portion received in an inverted cup 30 on an arm 31 of a fixed bracket 32, said brackets being made fast to the building by screw bolts 33 or any other suitable fashion.

15 Since the rod 17 is held against outward movement by the arms 19 and 28, and against downward movement by the arm 20 and upward movement by the arm 31, it will be clear that the guard 12 is secured in closed position to remain there normally.

When an emergency rises, application of suitable force to either of the arms 20 or 31 will serve to release the rod 17. For example, a fireman may strike the arm 29 a downward or downwardly 25 inclined blow with his ax and deform it so as to remove it out of the path of the lower end of the rod 17 and permit the rod to be withdrawn from the openings 18 and 27, thereby releasing the guard 12 to swing to the right in Fig. 1. Also, the fireman may strike a similar upward or upwardly inclined blow on the arm 33 and remove it from the upper end of the rod 17.

The bracket generally indicated by 22 is well adapted to be made in two parts by bending up bar stock and riveting or welding them together.

35 It also lends itself to casting.

The bracket 32 is well adapted to be made by casting or by bending bar stock and welding the inverted cup 30 to the arm 31. These variations will serve to suggest the wide range of forms in 40 which the invention may be embodied out of familiar materials and yet fasten the guards securely for normal conditions while yielding to suitable force under emergency to release the guard quickly.

Because there is some demand for guards to be readily locked and unlocked for window cleaning and other servicing, the bracket 22 is shown as having a slot 35 adapted to receive a staple 36 fixed to a bracket 37 made fast to the wall as by bolts 38. With such an arrangement, a padlock 39 may be used to secure or release the bracket 23, and when released it can by a suitable tilting be removed so as to release the rod 17.

In Fig. 4, there is shown a bracket, generally 50 indicated by 40, including a base portion 41

and a deformable arm 42 equipped with a cup 43 to receive the lower end of the rod 17. Such a bracket may be used with brackets shown at 29 and 32 in Fig. 1 to make up securing devices corresponding to those shown in Fig. 1 but without any padlock. They may be released by force applied with the fireman's ax or otherwise in an emergency.

When the securing devices include brackets of cast gray iron, the deforming blows may, 10 and usually will, result in breakage. When made of other familiar materials, the deforming will include bending, or bending and twisting or other distortion.

In Fig. 5, the guard 12 is fastened by rods 44 15 and 45, similar to the rod 11. At the left of Fig. 5, the upper end of the rod passes through an opening 46 in the arm 47 of a bracket 48 secured to the wall by bolts 49. The lower end of the rod 44 passes freely through an opening 20 50 in an arm 51 of a bracket 52 fastened to the wall. Its extreme lower end fits in a cup 53 in an arm 54 of a bracket 55 secured to the wall.

A limiting collar 56 fitting beneath the arm 51 prevents the rod 44 from being lifted out 25 of the cup 53, and hence it is made secure until the deforming force is applied. This may, again, be a blow with a fireman's ax against the arm 54 or the arm 54 and the cup 53. As an alternative, the blow may be applied to the extreme 30 upper end of the rod 44 to drive it through the cup 53, which may be made of a variety of materials—for example, glass of the kind commonly used in insulators for cross arms, terra cotta, porcelain, and a great variety of other plastic 35 materials.

In Fig. 8, the arrangement is similar, and the cup 57 holding the lower end of the rod 44 is made of pressed sheet metal that may either be pierced by the bottom end of the rod 44 or 40 driven through the opening 58 in the arm 54. Of course, in this form also, the force may be such as to deform the arm 54 with or without disturbing the cup 57.

At the right of Fig. 5, the arrangement is 45 somewhat similar to that shown in Figs. 6, 7, and 8, except that the rod 45 passes through the rails 15 and forms a hinge.

In Fig. 9, the arrangement corresponds to that shown in Figs. 5, 6, 7, and 8, except that the 50 rods 13 of the guard are horizontal and the rails 15 are vertical. With that arrangement, the guard can be released at the top and swung downwardly to form a part of a fire escape.

The securing devices here illustrated lend 55 themselves equally well to existing guards whereby the safety features of the buildings can be brought up to date at low cost. They also lend themselves to new installations. In many of the latter, instead of applying the hinges and brackets to the window frame, they may be advantageously applied to the building remote enough from the window frame to insure that an inmate cannot reach the deformable portion, either with 60 hands or with such objects as may accidentally become available within the building.

The forms and materials mentioned and illus-

trated are intended to be suggestive only, because of the great variety that is possible.

I claim:

1. A device for securing a hinged openwork 5 guard which extends across an opening in a building which comprises, a latching rod engaging an exterior portion of said openwork guard, means for securing said latching rod against outward movement relative to said opening, a laterally extending arm having a body portion fixed to said building and a locking portion abutting one end of said latching rod to prevent movement thereof axially in one direction, said locking portion being formed of a material and shaped so as to be readily deformable in response to a force applied thereto to release said latching rod for movement in said one direction, and means engaging said latching rod to prevent axial movement thereof in the opposite direction.

2. A guard for an opening in a wall of a building comprising an openwork guard across said opening, a bracket attached to and extending from said wall adjacent one side of said opening, said bracket having a portion extending outwardly beyond said openwork guard and having an opening, a latching rod inserted through said opening and engaging said openwork guard, and arms attached to said wall and abutting the ends of said rod, said arms being formed of a material and shaped for ready deformation in response to a force applied thereto but being otherwise relatively immovable, whereby said rod and said openwork guard are held against movement prior to deformation of one of said deformable arms.

3. A device for securing an openwork guard in normally closed position across an opening in a building, comprising a latch, means for positioning said latch in engagement with the guard to fix the latter against movement, and means for locking the latch in engagement with the guard comprising an arm having a body portion and a locking portion, means for attaching the body portion to a building with the locking portion in engagement with the latch to hold the latter in locking position, said locking portion being formed of a material and shaped so as to be readily deformable in response to a force applied thereto to release said latch.

4. A device of the type set forth in claim 3 in which said locking portion is formed of a frangible material.

5. A device of the type set forth in claim 1 in which said locking portion comprises a frangible insert in said arm.

GILBERT S. WATTERS.
